United States Patent

Des. 235,727
Patented July 8, 1975

235,727

FIREPLACE GRATE

Joseph S. Parziale, 8922 Wilson Mills Road,
Chesterland, Ohio 44026

Filed Aug. 30, 1974, Ser. No. 502,053

Term of patent 7 years

Int. Cl. D7—08

U.S. Cl. D7—207

The single figure of the drawing is a perspective view of a fireplace grate showing my new design.

I claim:

The ornamental design for a fireplace grate, as shown and described.
